UNITED STATES PATENT OFFICE

92,796

DESIGN FOR A CANDLE HOLDER

Ralph Erling, Alexandria, Va.

Application April 25, 1934, Serial No. 51,513

Term of patent 3½ years

To all whom it may concern:

Be it known that I, RALPH ERLING, a citizen of the United States, residing at Alexandria, in the State of Virginia, have invented a new, original, and ornamental Design for Candle Holders, of which the following is a specification, reference being had to the accompanying drawing, forming part thereof.

Figure 1 is a plan view of a candle holder, showing my new design; and Figure 2 is a side elevation of the same.

I claim:

The ornamental design for a candle holder, as shown.

RALPH ERLING.
